UNITED STATES PATENT OFFICE.

SAMUEL PITTS, OF STRONGHURST, ILLINOIS.

LOCK FOR THROTTLE-LEVERS.

1,162,307.

Specification of Letters Patent.

Patented Nov. 30, 1915.

Application filed January 3, 1914. Serial No. 810,249.

To all whom it may concern:

Be it known that I, SAMUEL PITTS, a citizen of the United States, residing at Stronghurst, in the county of Henderson and State of Illinois, have invented certain new and useful Improvements in Locks for Throttle-Levers, of which the following is a specification.

This invention relates to an improved throttle lever, and the principal object of the invention is to provide an improved lock whereby the lever may be held in a closed position to prevent an unauthorized person from starting the machine.

Another object of the invention is to so construct the lock that the lever may be left in a position to permit the engine to run slowly and prevent the throttle from being opened any wider.

Another object of the invention is to so construct the lock that while the lever can not be moved to open the throttle any wider, it may be moved to entirely close the throttle without releasing the lock.

This invention is illustrated in the accompanying drawings wherein—

Figure 1 is a view showing the lever in a locked position, one of the side walls being broken away to show the manner of mounting the lock carried by the lever. Fig. 2 is a vertical sectional view taken along the line 2—2 of Fig. 1; Fig. 3 is a fragmentary view of the latch lever to show that portion of the lever containing the locking disk.

The numeral 10 indicates the outer-end portion of the valve stem leading from a suitable throttle valve not shown. The outer end portion 11 of this valve stem 10 is reduced and has rigidly mounted thereon a latch lever by means of which the valve stem 10 may be turned. This latch lever is formed of two longitudinally-extending sections 12 and 13 which are secured at their free ends by means of the handle knob 14 and which have their inner faces cut to form a passageway 15. The arcuate segment 16 passes through the passageway 15 and is provided upon its lower edge with teeth which are engaged by a pawl carried by the lever.

A rod 17 is slidably mounted in a guide way 18 formed by abutting grooves in the sections 12 and 13 and is yieldably held in the normal position shown in Fig. 2, by means of a spiral spring 19 carried by the pin 20 and engaging the reduced lower end

21 of the rod 17. The operating pin 22 is carried by the rod and extends through a slot 23 formed in the section 12 to permit the rod to be moved downwardly against the tension of the spring 19 to a position to permit the securing pin 24 to be pressed inwardly against the tension of the spring 25 into a slot 26 formed in the upper-end portion of the rod 17.

A pawl 27 is slidably mounted in the upper end portion of the guide way 18 and is provided with a longitudinally-extending opening 28 in which fits the reduced upper end 29 of the rod 17. A spiral spring 30 is coiled about the reduced upper-end portion 29 of the rod 18 and engages the lower end of the pawl 27 to normally hold the pawl in engagement with the teeth of the segment 16. The upper end 31 of the pawl is beveled so that when the pawl is in engagement with the teeth, the lever may be moved toward the right-hand end of the segment shown in Fig. 1, but will be prevented from moving toward the left-hand end of the segment. A pin 32 extends transversely through the opening 28 of the pawl and passes through a cut-out portion 33 formed in the upper-end portion of the rod 17 to limit the longitudinal movement of the pawl and prevent the pawl from becoming disengaged from the rod.

A locking disk 34 is rotatably mounted in a circular pocket 35 by means of its pivot shaft 36 and carries a tooth 37. This tooth 37 is engaged by one end of a spring 38 which spring normally tends to rotate the disk 34 and move the tooth into a notch 39 formed in the rod 17. The section 12 of the lever is provided with an enlargement forming a cover 40 positioned in alignment with the pocket 35 and provided with a keyhole 41 through which a key may be inserted to engage the heel 42 of the tooth 37 and rotate the disk 34 to move the tooth out of the notch 39.

This improved rack lever is intended to be used particularly upon motor cycles and automobiles so that when the motor cycle is left at the curb, the rod may be released and permitted to assume the position shown in Figs. 1 and 2. When in this position, it will be impossible for an unauthorized person to take the machine since while the lever may be moved to stop the running of the motor, the lever can not be moved in the opposite direction to open the throttle valve.

The pawl 27 by being slidably mounted and yieldably held in a normal position by the spring 30 permits the lever to be moved toward the right of Fig. 1 to close the 5 throttle valve without the lock being released. When it is desired to use the machine, a key is inserted in the keyhole 41 and is turned to engage the heel 42 and rotate the disk 34, thus moving the tooth 10 out of the notch 39. The rod 17 can then be moved downwardly by means of the pin 22 and the pin 24 moved into the socket 26. The resiliency of the spring 19 will cause a 15 binding action between the inner end of the pin 24 and the bottom portion of the socket 26 and this will hold the rod in the lowered position with the pawl out of engagement with the segment 16. The key can then be withdrawn and the rod will 20 remain in the lowered position. As soon as the rider has no further use for the machine and wishes to leave it at the curb or in a storage place, the lever may be moved to entirely or partially close the throttle valve 25 and the pin 22 can then be moved slightly downwardly thus causing the pin 24 to be moved outwardly by the spring 25 and permit the rod to be moved upwardly by the spring 19. As soon as the rod is moved 30 upwardly a sufficient distance, the spring 38 will force the free end of the tooth 37 into the notch 39 and securely lock the rod in the position and prevent the lever from being moved to open the throttle valve.

35 What is claimed is:

1. A lever provided with a transversely-extending passage way and with a longitudinal-guide way leading from said passage way and being also provided with a pocket 40 positioned intermediate the length of said guide way, a rod slidably mounted in said guide way, a segment passing through said passage way, a pawl slidably mounted within said guide way upon one end of said rod, 45 a spring coiled about said rod and engaging said pawl to yieldably hold the pawl in engagement with said segment, a spring mounted in the opposite-end portion of said guide way and engaging the end of said rod for yieldably holding said rod in a normal 50 position, a disk rotatably mounted in said pocket, a tooth carried by said disk, a spring engaging said tooth for normally holding said disk in a position for said tooth 55 to enter a notch formed in said rod, and said lever being provided with an opening through which a key may be passed to engage said tooth and rotate said disk to move

said tooth out of the notch formed in said rod.

60 2. A lever provided with a longitudinally-extending guide way, a rod slidably mounted in said guide way, a locking pawl slidably mounted upon said rod, means for yieldably holding said pawl in a normal position, 65 means for yieldably holding said rod in a normal position, locking means, and means for yieldably holding said locking means in a normal position to engage said rod.

70 3. A lever, a carrying element slidably connected with said lever, means for yieldably holding said carrying element in a normal position, an engaging element slidably mounted upon the outer-end portion of said carrying element, means for yieldably holding said engaging element in a normal position, a locking element, and means for normally holding said locking element in a position 75 to engage said carrying element.

80 4. A lever, a carrying member slidably connected with said lever, an engaging member movably carried by said carrying member, means for yieldably holding said carrying member and engaging member in a normal position, means for moving said carrying member and engaging member against the tension of the resilient means and holding said carrying member in a normal position, means for releasably holding said carrying member in an adjusted position, 85 and means for releasably locking said carrying member in an adjusted position.

90 5. A lever provided with a longitudinally-extending guideway, a rod slidably mounted in said guideway and provided with a notch, 95 a disk rotatably carried by said lever and provided with a tooth, resilient means for normally holding said disk in a position for its tooth to enter the notch of said rod and means for normally holding said rod in a 100 raised position.

105 6. A lever, a rod slidably carried by said lever, a locking element movably carried by said lever and adapted for interlocking engagement with said rod, means for normally holding said rod in a position to prevent interlocking engagement with said locking element, and means for normally holding said locking element in a position to engage 110 said rod.

In testimony whereof I affix my signature in presence of two witnesses.

SAMUEL PITTS.
